UNITED STATES PATENT OFFICE.

GEORGE H. SARGENT, OF CHICAGO, ILLINOIS.

RERAILER.

1,169,874.

Specification of Letters Patent.

Patented Feb. 1, 1916.

Application filed March 22, 1915. Serial No. 16,086.

To all whom it may concern:

Be it known that I, GEORGE H. SARGENT, a citizen of the United States, and resident of Chicago, in the county of Cook and State of Illinois, have invented certain new and useful Improvements in Rerailers, of which the following is a specification.

My invention relates to rerailing and derailing devices and has particular reference to a novel rerailer adapted for use in street railway work.

An object in the construction of the present device is to provide a rerailer which may be exceedingly light and of small size. In street car work it is, of course, unnecessary to provide for the same elevation of the wheels as in steam railroad work but many difficulties have been encountered in producing a rerailer which shall be efficient in all situations and which shall be of sufficiently light weight and small size to warrant a pair thereof being carried by each car.

A further object is to provide a rerailer which is adapted to engage the tread of the wheel instead of the flange, thereby insuring a greater tractive effort and obviating flange breakage.

A still further object is to provide a device of this sort in which the portion of the device first engaging the wheel shall be very shallow to the end that the wheel need not overcome an abrupt incline in order to engage the rerailer.

A further advantage in the present construction is in providing the wheel engaging inclines with corrugations or roughened surfaces at the point of first engagement of the wheel therewith, this in conjunction with the fact that the tread of the wheel is engaged and a comparatively great tractive surface is afforded which assures the easy engagement and elevation of the wheel without the danger of flange breakage.

The invention will be more readily understood by reference to the accompanying drawings, wherein,

Figure 1 is a plan view of two of my rerailers associated in proper relation to the rails; Fig. 2 is a bottom plan view of one of the devices; Fig. 3 is a side elevation thereof; Fig. 4 is a side elevation from the opposite side to that of Fig. 3; Fig. 5 is a section on the line 5—5 of Fig. 1, showing the wheel in the first position after engaging the rerailers; Fig. 6 is a section on the line 6—6 of Fig. 1, showing the next position of the

wheels, and Figs. 7 and 8 are sections on the line 7—8, 7—8 of Fig. 1, showing the wheels in the act of being rerailed.

The device consists essentially in a body portion 10, which is sloped as required, the high point being at the middle. There is the usual double angle of inclination resulting in a substantially cylindrical outline. This body portion is preferably cast hollow and is strengthened by transverse and longitudinal ribs 11, 12. This provides for separated points of contact with the ground or pavement and preferably these contact points including the ribs are corrugated to insure a gripping action. Extending in alinement on opposite sides of the body portion are projections 13, the upper surfaces of which, as shown in Figs. 3 and 4, are inclined downward toward the ends of the projections, the elevation of the ends being of an extent substantially equal to the height of the flange of a wheel. Thus a wheel may initially engage the projections on its tread surface without any material elevation of the wheel, it being understood that when derailed the wheels will rest upon their flanges. The upper surfaces of the projections 13 are flattened and corrugated, as at 14, thus providing a rather extensive area of contact along the tread of the wheel, the corrugations insuring the proper engagement and making the elevation of the wheel more certain.

Referring now to Figs. 5, 6, 7 and 8, it will be seen that the first engagement of the wheel 15, is on its tread portion 16, the tread engaging the flattened upper surface of the projections 13, and requiring substantially no elevation of the wheel in view of the contact of the flange 17 of the wheel with the ground or pavement. As the wheel is slightly elevated by traveling up the incline it arrives at the point 18, as best shown in Fig. 6, at which the area of contact of the tread with the rerailer is lessened. It is at about this point that the projection begins to merge into the body portion 10 of the rerailer. In the next position (Fig. 7), the wheel has ridden up until it is carried by the body portion and has begun to slide sideways due to the incline of the rerailer. The outside wheel, as shown to the right in Fig. 7, still has not contacted the rerailer with its flange, the tread carrying the entire load. The inside wheel, as viewed to the left in Fig. 7, is carried on its flange, the flange

having begun to slide down the incline. In Fig. 8 the position is shown as just preceding the rerailing of the wheels on the track, the outside wheel having slid down the incline on its tread and the inside wheel on its flange. Thus it will be seen that the two wheels are brought into proper position with relation to the track with a very slight elevation and with an assurance of operation because of the positive coöperation of the tread of the wheel with the corrugated point or nose of the leading projections. A pair of devices constructed as described have been found extremely efficient in service and each replacer weighs approximately 15 pounds. Contrasting this with the weight of the devices commonly in use it will be seen that there is much in favor of my rerailer.

20 While the device has been described solely as a rerailer, it will be understood that it acts equally well as a derailler, the necessity for such use arising in street car work with frequency, particularly where cars are compelled to cross over at a certain location due to fires or blockades at which point there is no cross-over track. The device will also be found to be efficient for derailing heavily loaded wagons which find it impossible to get out of the track. The exact angles and form of the device shown in the drawings are not essential to the satisfactory operation thereof and I therefore do not wish to be limited to the exact form shown and described.

25 I claim:

30 1. In a rerailer, the combination of a body of metal, the upper surface of which is curved, and a narrow tread-engaging arm projecting from each side of said body portion, said arms lying in substantial alinement and being joined to said body portion

35 at a point substantially midway between the side edges thereof, substantially as described.

2. In a device of the class described, the combination of a body of metal having a double angle of inclination, and a pair of narrow, oppositely projecting, substantially alined, tread-engaging arms integral with said body portion and joined thereto at a point between the side edges thereof, substantially as described.

3. A rerailer composed of a convexed body of metal, and a pair of integral, narrow, oppositely extending, inclined arms, said arms being joined to the body of the rerailer at a point substantially midway between the side edges thereof, the upper surface of said arms being adapted to engage the tread of a wheel, the vertical thickness of the end of each arm being substantially equal to the height of a wheel flange, substantially as described.

4. A rerailer composed of a convexed body of metal and a pair of oppositely projecting substantially alined arms which merge into such convexed portion, the upper surface of the ends of such projections being flattened and corrugated, substantially as described.

5. A rerailer composed of a convexed body of metal and a pair of arms projecting in substantial alinement from opposite ends of said body of metal, said arms being relatively narrow, the upper surface of the ends of the arms being flattened and corrugated and adapted to engage a wheel tread, substantially as described.

Signed at Chicago, Ill., this 18th day of March, 1915.

GEORGE H. SARGENT.
